DESIGN FOR A PIANO ACCORDION

Otto Schmidt (also known as Otto Sorosoto), De Kalb, Ill., assignor to Wurlitzer Grand Piano Company, De Kalb, Ill., a corporation of Illinois

Application April 5, 1935, Serial No. 56,235

Term of patent 7 years

To all whom it may concern:

Be it known that I, Otto Schmidt (also known as Otto Sorosoto), a citizen of the Netherlands, having residence at De Kalb, in the county of De Kalb and State of Illinois, have invented a new, original, and ornamental Design for a Piano Accordion, of which the following is a specification, reference being had to the accompanying drawing, forming a part thereof.

In the drawing:

Figure 1 is a perspective view of a piano accordion embodying my new design.

Figure 2 is a top plan view thereof with the carrying strap being shown broken away.

Figure 3 is an end view.

I claim:

The ornamental design for a piano accordion, substantially as shown and described.

OTTO SCHMIDT.
